(57) **CLAIM**

The ornamental design for a camera stand, as shown and described.

DESCRIPTION

FIG. 1 is a front perspective view of a camera stand showing my new design;

FIG. 2 is a side perspective view of FIG. 1 with the lid closed; and,

FIG. 3 is a side perspective view of FIG. 1 with the lid open. The broken lines shown in FIGS. 1 and 3 are for illustrative purposes only and form no part of the claimed design.

1 Claim, 2 Drawing Sheets

FIG. 1
